UNITED STATES PATENT OFFICE.

HARRY L. WARD, OF LONG BEACH, CALIFORNIA.

AUXILIARY AIR-INLET AND HUMIDIFIER FOR THE MANIFOLD OF AN INTERNAL-COMBUSTION ENGINE.

1,202,458.

Specification of Letters Patent. Patented Oct. 24, 1916.

Application filed January 21, 1916. Serial No. 73,330.

To all whom it may concern:

Be it known that I, HARRY L. WARD, a citizen of the United States, residing at Long Beach, in the county of Los Angeles and State of California, have invented new and useful Improvements in Auxiliary Air-Inlets and Humidifiers for the Manifold of an Internal-Combustion Engine, of which the following is a specification.

10 My invention relates to an auxiliary air inlet and humidifier for the manifold of an internal combustion engine of an automobile.

15 It is an object of this invention to construct an auxiliary air inlet and humidifier for the manifold of an internal combustion engine in which a supply of air and water to the manifold is controlled by a single valve actuated by a single operating means within convenient reach of the driver.

20 It is another object of this invention to construct an auxiliary air inlet and humidifier of the kind referred to which will not flood the carburetor with water in case the operator should neglect to close the air and water control valve or the cut-off valve in 25 the conduit leading from the water reservoir to said humidifier.

With the foregoing and other objects in view which will appear as the description 30 proceeds, my invention consists in the novel features of construction, arrangement and combination of parts hereinafter described and claimed.

In the accompanying drawings which form 35 a part of this specification, I have illustrated a convenient and practical embodiment of my invention, and in which:

Figure 1 is a side elevation of an internal combustion engine of an automobile showing my device applied to the manifold thereof. Fig. 2 is a cross-sectional view of the combined air and water valve attached to the manifold. Fig. 3 is a sectional view taken on line 3-3, Fig. 2.

40 The manifold 10 of an internal combustion engine of a motor driven vehicle is provided with a screw threaded aperture 11 adapted to receive in screw threaded relation the threaded end or outlet port 12 of a cylindrical valve casing 13 which slants 45 downwardly therefrom at a slight angle from the horizontal. The bore 14 of the valve casing 13 is slightly tapered toward the manifold end and is provided with a 50 plurality of air inlet ports 15 circumferen- 55

tially arranged on the periphery of the casing. A plunger valve 16 is slidably mounted in said valve casing and is operated from the driver's seat by means of a hand lever 17 pivoted to the upper end of the steering 60 post 18, said hand lever being connected to the outer end of the plunger valve 16 by a wire 19 which passes through an apertured cap 20 screwed in the outer end of the valve casing. An expansible coiled spring 21 disposed between cap 20 and the plunger valve tends to move the latter into closed position. The valve casing 13 is provided at its lower side with a downwardly projecting nipple 22 providing a water inlet port 23 which is 65 counterbored at 24 to receive in screw threaded relation the upper end of a T-shaped needle valve casing 25. The water enters the valve casing at the nipple 26 of the needle valve casing 25, the water being supplied 70 from a water tank 27 secured at any suitable place to the automobile and connected with nipple 26 by a fluid connection 28. A cut-off valve 31 is provided in said fluid connection whereby the water may be shut off 75 to the needle valve casing 25. A needle valve 29 controls the water to the port 23, leading into the valve casing 13, said needle valve being rotatably mounted in the lower end of the needle valve casing 25 and provided with a manually operated head 30.

From the foregoing description the operation of the combined air inlet and water valve will be easily understood. The water is supplied from the water tank 27, the cut-off valve 31 being open. The amount of water supplied to the valve casing 13 through the water inlet port 23 is controlled by the adjustment of the needle valve 29. It should be noted that the water inlet port 90 23 in the valve casing 13 is situated between the air inlet ports 15 and the outlet port 12 leading to the manifold. After the engine has been started and it is desired to feed water and air so as to properly dilute the 95 gaseous mixture supplied by the carburetor to the engine, the plunger valve 16 is operated. Air will now enter the valve casing through the inlet ports 15 and will be sucked by the action of the engine, into the manifold. It should be noted that the air will flow in the annular passage formed between the plunger valve 16 and the valve casing 13. The water entering said valve casing 100 from the needle valve casing will be forced 105 110

along the bottom of the valve casing 13 up the slight inclination and into the manifold by the current of air flowing between the plunger valve 16 and the valve casing 13.

- 5 The advantages of proper dilution of the gaseous mixture flowing into the engine when the latter is running at high speed is well understood, likewise the advantages of feeding water with the gaseous mixture.
- 10 Not only is the action of the internal combustion made more uniform but carbon deposits are prevented. In case carbon deposits are present in the cylinders of the engine, they are softened by the steam generated
- 15 from the water fed with the gaseous mixture, and are subsequently blown out. I have found that a saving of fuel and a smoother running of the engine is effected by feeding a small quantity of water with
- 20 the fuel at all times. The maximum proportion of water to liquid fuel may reach as high as 25 per cent. of the fuel consumption.

If the operator of the car should neglect to close the cut-off valve 31 in the water feed pipe or the plunger valve 16 which simultaneously controls the air and water feed to the manifold, the flooding of the carburetor will be prevented by reason of the fact that the valve casing 13 is at a slight angle of inclination, and any water flowing from the water inlet port into the plunger valve casing 13 will flow downwardly and out of the lower air inlet port 15.

It is thus seen that I have devised a combined auxiliary air and water inlet device for the manifold of an internal combustion engine which is exceedingly simple of construction, positive in operation, controlled by a single operating mechanism from the driver's seat and which will positively prevent the flooding of the carburetor with water in case the operator fails to shut off the water supply after the engine has been stopped.

45 I claim:

1. The combination of a manifold of an internal combustion engine of an automobile, a combined air and water valve having an outlet port connected to said manifold, said valve comprising a casing slanting downwardly from said outlet port, a plurality of air inlet ports arranged circumferentially on the periphery of said casing, a water inlet port in the under side of said casing and disposed intermediate said air inlet ports and said outlet port, a valve con-

trolled water feed pipe leading to said water inlet port, a needle valve in said pipe controlling the water feed to said water inlet port, a conical plunger valve slidably mounted in said casing and controlling said air and water inlet ports and manually operated means under the control of the driver for operating said plunger valve.

2. The combination of a manifold of an internal combustion engine of an automobile, a combined air and water valve having an outlet port connected to said manifold, said valve comprising a casing slanting downwardly from said outlet port, a plurality of air inlet ports in said casing, a water inlet port in said casing intermediate said air inlet ports and said outlet port, a valve controlled water feed pipe leading to said water inlet port, a conical plunger valve slidably mounted in said casing and controlling said air and water inlet ports and manually operated means under the control of the driver for operating said plunger valve.

3. The combination of a manifold of an internal combustion engine of an automobile, a combined air and water valve having an outlet port connected to said manifold, said valve comprising a casing slanting downwardly from said outlet port, an air inlet port in said casing, a water inlet port in said casing intermediate said air inlet port and said outlet port, a valve controlled water feed pipe leading to said water inlet port, a valve controlling said air and water inlet ports and manually operated means under the control of the driver for operating said valve.

4. The combination of a manifold of an internal combustion engine, of an automobile, a combined air and water valve having an outlet port connected to said manifold, said valve comprising a casing slanting downwardly from said outlet port, an air inlet port in said casing in the bottom side thereof, a water inlet port in said casing intermediate said air inlet port and said outlet port, valve controlled means for feeding water under pressure to said water inlet port, a valve member controlling said air and water inlet ports, and manually operated means under the control of the driver for operating said valve.

In testimony whereof I have signed my name to this specification.

HARRY L. WARD.
